WALTER H. KNISKERN, OF SYRACUSE, NEW YORK, ASSIGNOR TO ATMOSPHERIC NITROGEN CORPORATION, OF SYRACUSE, NEW YORK, A CORPORATION OF NEW YORK.

HEAT EXCHANGER.

Application filed August 16, 1923. Serial No. 657,675.

My invention relates to heat exchangers of the type which include nests of tubes in which gases or other fluids are brought into heat exchanging relation to each other and has for its object to provide an improved and simplified construction in which a uniform annular space for gas passage in each tube is maintained and in which the inter-relation of the elements constituting the exchanger is accurately predetermined. The invention contemplates further the provision of an arrangement in which any pressure differential between the heat exchanging gases or fluids in the apparatus is utilized to maintain the same in an operative condition. A further object of the invention is to provide an improved packing and gland whereby a satisfactory connection between the nest of tubes and the shell containing the same is insured. Other objects of the invention will appear from the description hereinafter.

In the accompanying drawings, which illustrate an example of the invention without defining its limits, Fig. 1 is a sectional elevation of a heat exchanger embodying the invention; Fig. 2 is an enlarged, fragmentary section thereof; Fig. 3 is an enlarged cross-section of one of the tube elements; Fig. 4 is an enlarged detail section of an improved gland and packing arrangement; Fig. 5 is a horizontal section on line 5—5 indicated on Figs. 1 and 6 and Fig. 6 is a fragmentary vertical section on line 6—6 of Fig. 5.

As shown in the drawings the apparatus may comprise a shell 10 preferably cylindrical in form and of predetermined length suitable for the intended purpose and provided at opposite ends with removable heads 11 and 12, respectively, secured in place, for instance, by means of bolts 13. Each head is provided with inlet and outlet openings which, in the present case, have been indicated respectively as 14 and 15 in the head 11 and 16 and 17 in the head 12. The shell 10 may be supported in its operative position in any suitable manner as by means of a conventional supporting bracket 18.

Within the shell 10 is located the improved tube nest, which, as shown in Fig. 2, comprises tubes 19, rolled or expanded into or otherwise connected at their opposite ends with tube sheets 20, said sheets being connected with plates 21 by means of bolts 22 and

held in spaced relation thereto by means of the rings or spacers 23 through which the bolts 22 pass as shown in Fig. 1, the sheets 20, plates 21, and spacers 23 forming units which may be termed headers. A gas-tight condition is maintained at this point by using a ground joint between the rings 23 and the tube sheets 20 and the plates 21. Core-rods 24 extend lengthwise of the tubes 19 and are provided at regular spaced intervals with projections 25 extending outwardly from said rods 24 into contact with the interior surfaces of the tubes 19 as shown in Fig. 2; the projections 25 as shown in the drawings may be arranged in pairs lengthwise of the rods 24 and preferably so that the projections of one pair are out of registry with the projections of adjacent pairs, said projections serving to maintain the cores centrally within the tubes 19 and to maintain uniform annular spaces 26 therein for the passage of gases or other fluids. By substituting core-rods of different dimensions, the interchanger may readily be adapted for differing degrees of heat interchange according to the resultant variation in gas velocity. As shown in Fig. 2 some of the core-rods 24 may be supported by resting upon the bottom plate 21 while others of said cores, that is, those which lie above the outlet 17, may be suspended from the upper tube sheet 20 in any suitable manner; for instance, the upper ends of the last-mentioned group of core-rods may be flattened as indicated at 24^a in Fig. 2 to provide rigid devices spanning the openings of tubes 19 and having a transverse width materially less than the internal diameter of the tubes whereby the full area for gas passage is, at the same time, maintained. If desired baffle plates 27 and 27^a may be located in registry with the openings 14 and 17, respectively.

As shown in Fig. 1 a tube 28 is screw-threaded into the bottom plate 21 and depends therefrom into the opening 17 in which suitable packings held in place by suitable devices 29 are located to provide a fluid-tight connection. A similar tube 30 is screw-threaded into the upper plate 21 and extends into the opening 14 of head 11 which is shown as provided at the inner end of opening 14 with an annular shoulder 14^a surrounding the tube 30. The connection between the latter and the head 11 is, how-

ever, preferably made by the improved gland and packing arrangement shown in detail in Fig. 4 and which comprises a first ring 31 which surrounds the tube 30 and rests against an annular shoulder 32 formed thereon (or on 14^a of 11). A series of split packing rings 33 and 34 alternately bevelled in opposite directions rest against each other and against the bevelled face of the ring 31; 10 a second ring 35 having one of its faces bevelled rest against the terminal packing ring 34 in the present case, and, in turn, is engaged by a gland 36 screwed upon the externally screwthreaded end 37 of the tube 30 (or into 15 11, if a shoulder thereof is used for ring 31). All of the rings 33 and 34 are preferably made of steel and the faces of the rings are cut at an angle as shown so that as pressure is applied thereto by the adjustment of 20 the sleeve nut 36, alternate rings 33 and 34 will make contact respectively with the tube 30 and with the head 11 and thereby provide a satisfactory connection. This arrangement is independent of the external 25 flange and pipe connection 38 whereby a pipe 39 extending from a source of fluid supply may be connected with the apparatus. It will be understood that similar pipes 39^a, 39^b and 39^c constituting inlet and outlet pipes 30 are likewise connected with the apparatus in the well-known way.

In utilizing the heat exchanger a gas or other fluid passes into the apparatus through the inlet 16 and circulates through the shell 35 10 upon the outside of the tubes 19 and passes out through the outlet 15 while a gas or other fluid at a different temperature is caused to flow through the pipe 39 and tube 30 and through the annular spaces 26 interiorly of the tubes 19 and finally passes out 40 through the tube 28 and pipe 39^c.

If the heat exchanging fluids are at different pressures, the one at the higher pressure is introduced at 16 and the one at the 45 lower pressure at 14, through the pipes 39 and tube 30. This condition often exists and the pressure differential may be considerable as for example where the heat exchanger forms part of a reaction system in which the 50 heat exchanging fluids are respectively those going to and those coming from the reaction vessel or vessels. By thus passing the gas or other fluid of a higher pressure outside of the tubes 19 and the gas or other fluid of 55 a lower pressure through the tubes, the tendency of any pressure differential in the apparatus is to press the tube sheets toward the plates 21 which pressure is resisted by the spacers 23^a, which are from one to two 60 thousandths of an inch shorter than the ring 23 is thick. The spacers may be of any suitable type and as shown comprise members provided at one of their ends with reduced portions adapted to fit into suitable 65 recesses located for this purpose on the

plates 21; in order to make the spacers 23^a reversible the aforesaid reduced portions may be duplicated at opposite ends thereof, as shown in Fig. 1. The bulging of the tube sheets 20 and of the plates 21, because 70 of pressures in the apparatus, is thereby resisted and the pressure differentials themselves are utilized to maintain these parts of the apparatus in an efficient condition.

The flow of gases may obviously be reversed so that 15 and 17 are used as inlets and 16 and 14 as outlets.

The arrangement of core-rods 24 within the tubes 19 is such that uniform annular spaces 26 are maintained within said tubes 80 through which the gas or other fluid passes in relatively thin sheets, whereby a desirable heat exchange effect resulting from small cross-section and corresponding high gas velocity is efficiently obtained.

In the preferred arrangement it is desirable to cause that gas, which passes around the tubes 19, to follow a sinuous path during such passage in order that a maximum heat exchange may take place in the apparatus. 90 For this purpose baffle plates 40 extend transversely across the tubes 19 in a manner to divide the spaces therebetween into a sinuous passage as shown in Fig. 1. In the illustrated example these baffle plates 40 are supported by means of sections 41 located in registry with each other and extending between the baffle plates as shown in Fig. 6; in order to clamp the baffle plates 40 in place, angle irons 42 may be riveted to the sections 41 and to alternate baffle plates 40 as shown in Fig. 6, the intermediate plates 40 being clamped between the opposed edges of contiguous sections 41. The latter sections 41, as shown in Fig. 5, are spaced from the shell 10 and form spaces 43, said sections preferably following the interior form of said shell and being preferably relatively small in width, as small as the angle irons 42 will allow. To prevent the gases from passing through the spaces 43 between the sections 41 and the shell 10 and to force said gases to pass between the tubes and over the surfaces of the baffle plates 40, flanges 44 are provided whereby the spaces 43 are formed into dead spaces and closed against communication with the sinuous passage defined by the baffle plates 40. These flanges 44 may be of any suitable construction and arrangement and in the illustrated example extend 105 between the sections 41 and comprise integral portions of said sections 41 which project from opposite ends thereof. As shown in Fig. 5, these flanges 44 sufficiently prevent the gases from finding a ready passage along the spaces 43 to force said gases to pass through the tube nest in the predetermined sinuous direction instead of around it.

The improved gland and packing arrangement shown in detail in Fig. 4 provides not 120

only an efficient joint between the pipe 30 and the head 11, but also forces and holds the packing in position between the shoulder 32 of the tube 30 and the gland 36. Furthermore, with the arrangement set forth and illustrated, the desirable free movement of the tube nest within the pressure shell which is necessary to compensate for temperature changes in said tube nest is obtained and at the same time the detachable relation between the tube 30 and the head 11 is maintained throughout the life of the apparatus so as to permit of the ready disconnection of the parts when, for any reason, this is required as the rings 33, 34 neither freeze nor disintegrate.

The materials of construction may be suitably varied in accordance with the temperature and other conditions and the nature of the heat exchanging fluids. For example, for a nitrogen-hydrogen gas at high pressures and temperatures (used in ammonia synthesis) the rings 33, 34, the tubes, the tube sheets, the plates, the spacers, the shell 25 and the shell heads are preferably constructed of chrome vanadium steel or other suitable resistant alloy.

Various changes in the specific form shown and described may be made within the scope of the claims without departing from the spirit of my invention.

I claim:

1. In a heat exchanger, the combination of a vertical casing forming a conduit for a fluid, a nest of vertical tubes opening at their upper and lower ends into headers located within said conduit but having no communication with the conduit and arranged to convey a second fluid in heat exchange relation to said first fluid, connections establishing communication between the exterior of the casing and the spaces within the tubes, one of said connections having a port opening into the lower of the two said headers beneath a plurality of said tubes and having a greater diameter than the sum of the diameters of said plurality of tubes, core-rods of substantially even external dimensions extending lengthwise of said open-ended tubes and defining annular passages therein for said second fluid, means within said open-ended tubes extending between the outer surface of each core-rod and the inner surface of each tube for centralizing the core-rods in said tubes and for maintaining them in uniform spaced relation to said tubes, and a rigid device located exteriorly of the tubes, at the upper end of each of those core-rods which are located above the aforementioned port, said rigid device spanning its tube and having a transverse width materially less than the internal diameter of its tube, whereby each of said core-rods is suspended by the device in its open-ended tube without obstructing the accessibility at the points of

suspension, of the free spaces within said tubes.

2. In a heat exchanger, the combination of a vertical casing forming a conduit for a fluid, a nest of vertical tubes opening at their upper and lower ends into headers located within said conduit but having no communication with the conduit and arranged to convey a second fluid in heat exchange relation to said first fluid, connections establishing communication between the exterior of the casing and the spaces within the tubes, one of said connections having a port opening into the lower of the two said headers beneath a plurality of said tubes and having a greater diameter than the sum of the diameters of said plurality of tubes, core-rods of substantially even external dimensions extending lengthwise of said open-ended tubes and defining annular passages therein for said second fluid, projections extending outwardly from the surface of each core-rod at spaced intervals for centralizing each core-rod in its open-ended tube and for maintaining it in uniform spaced relation thereto, and a rigid projection located exteriorly of the tubes at the upper end of each of those core-rods which are located above the aforementioned port, each rigid projection spanning its tube and having a transverse width materially less than the internal diameter of its tube, whereby each of said core-rods is suspended by its projection in its open-ended tube without obstructing the accessibility, at the points of suspension, of the free spaces within said tubes.

3. In a heat exchanger, the combination of a vertical casing forming a conduit for a fluid, a nest of vertical tubes opening at their upper and lower ends into headers located within said conduit but having no communication with the conduit and arranged to convey a second fluid in heat exchange relation to said first fluid, connections establishing communication between the exterior of the casing and the spaces within the tubes, one of said connections having a port opening into the lower of the two said headers beneath a plurality of said tubes and having a greater diameter than the sum of the diameters of said plurality of tubes, core-rods of substantially even cylindrical dimensions depending into said open-ended tubes to define annular passages therein for said second fluid, projections extending radially outward from the surface of each core-rod at spaced intervals for centralizing each core-rod in its open-ended tube and for maintaining it in uniform spaced relation thereto, and a flattened rigid projection located exteriorly of the tubes, at the upper end of each of those core-rods which are located above the aforementioned port, each rigid projection spanning its tube and having a transverse width materially less than

the internal diameter of its tube, whereby each of said core-rods therein is suspended by its projection in its open-ended tube, without obstructing the accessibility, at the 5 points of suspension, of the free spaces with said tubes.

4. In a heat exchanger, a shell having inlet and outlet openings, a tube nest within said shell comprising tube sheets, a plurality of 10 tubes having their opposite ends fixed in said tube sheets, end plates connected with said tube sheets in fixed spaced relation thereto, upper and lower gas deflecting means associated with said inlet and outlet openings 15 respectively, core-rods extending lengthwise of said tubes to define annular fluid passages therein, some of said rods resting upon one end plate to maintain them in position in the tubes free from interference with said 20 upper deflecting means, flattened ends on others of said rods for suspending them in said tubes free from interference with the lower deflecting means and projections located at uniformly spaced intervals on said 25 rods for centralizing them in said tubes and for maintaining them in spaced relation thereto.

5. In a heat exchanger, the combination of a shell, a tube nest within said shell comprising a plurality of tubes, tube sheets for their opposite ends, an end plate located at a distance from one of said tube sheets and connected therewith, means for fixing said tube sheets and end plate in spaced relation 30 and for sealing the space therebetween to form a fluid-tight gas chamber between said tube sheets and end plate and spacers located at intervals between said tube sheets and end plate for maintaining the same against 35 collapse toward each other by gas pressures effective against them from the outer sides thereof, said spacers being of such dimensions as to present no interference to the sealing effect of the said fixing and sealing 40 means.

6. In a heat exchanger, the combination of a shell, a tube nest within said shell comprising a plurality of tubes, tube sheets for their opposite ends, an end plate located at a distance from one of said tube sheets and connected therewith, an annular member for fixing said tube sheets and end plate in spaced 50 relation and for sealing the space therebetween to form a fluid-tight gas chamber between said tube sheets and end plate, and spacers located at intervals between said 55

tube sheets and plate and connected with one of said elements for maintaining the same against collapse toward each other by gas pressures operative against them from the 60 outer sides thereof, said spacers being of such dimension as to prevent no interference to the sealing effect of the said fixing and sealing means.

7. In a heat exchanger, the combination 65 of a shell, a tube nest within said shell comprising tube sheets, a plurality of tubes having their opposite ends arranged in said tube sheets, an end plate spaced from one of said tube sheets and having a plurality of recesses, an annular member located between said tube sheets and end plate to space the same apart and to form a gas chamber therebetween, means for clamping said tube sheets and end plate against said member to 70 seal said chamber and a plurality of spacers located between said tube sheets and end plate to prevent the collapse thereof toward each other by pressures within said heat exchanger, and having reduced ends fitted into the recesses of said end plate, said spacers being of such axial length as to present no interference to the clamping of the end plate and tube sheets against said annular member. 75

8. In a heat exchanger, the combination of a shell, a tube nest within said shell, a plurality of baffle-plates extending transversely across said tubes to divide the spaces therebetween into a sinuous passage, a plurality 80 of sections extending between said baffle-plates to support the same in spaced relation, and flanges extending between the sections and said shell to provide dead spaces between said sections and said shell and to 85 force the gases to pass through said tube nest.

9. In a heat exchanger, the combination of a shell, a tube nest within said shell, a plurality of baffle-plates extending transversely 100 across said tubes to divide the spaces therebetween into a sinuous passage, a plurality of sections extending between said baffle-plates to support the same in spaced relation, and flanges extending from opposite 105 ends of said sections into engagement with said shell to provide dead spaces between said sections and said shell and to force the gases to pass through said tube nest.

In testimony whereof I have hereunto set 110 my hand.

WALTER H. KNISKERN.
